UNITED STATES PATENT OFFICE.

LESLIE H. PETER, OF LONDON, ENGLAND, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA.

ALTERNATING-CURRENT RELAY.

Application filed February 18, 1928, Serial No. 255,478, and in Great Britain February 15, 1927.

This invention relates to alternating current relays of the two element induction type in which the magnetic system of the relay comprises two distinct sets of poles, each of these sets comprising poles adapted to produce a torque upon the vane or movable element, the torque due to one set of poles being arranged to be opposite to that due to the other set, with the object of rendering the relay effectively responsive to alternating current of a particular frequency supplied to both windings or elements of the relay, and unresponsive to alternating currents of a different frequency.

The principal feature of the present invention is the provision of an improved form of core structure for the magnetic system of the relay whereby the opposing torques exerted upon the movable element are arranged to be more exactly balanced for the frequency at which it is desired that the relay shall be unresponsive, thus preventing any tendency of the movable element to creep towards its operative position under these conditions.

According to the present invention, this object is attained by so constructing the magnetic cores traversed by the corresponding fluxes causing the opposing torques, that these cores are physically and magnetically separate from one another, but are surrounded by or linked with an energizing winding or windings common to both cores.

I will describe one form of relay embodying my invention, and will then point out the novel features thereof in claims.

In the accompanying drawings, Fig. 1 is a view showing, in side elevation, one form of relay embodying my invention. Fig. 2 is a top plan view of a portion of the relay shown in Fig. 1 and is also a diagrammatic view showing one form of apparatus with which the relay may be used. Fig. 3 is a sectional view along the line III-III of Fig. 2. Fig. 4 is a sectional view along line IV-IV of Fig. 2.

Similar reference characters refer to similar parts in each of the several views.

Referring now to the drawings it will be seen that the magnetic system of the relay designated in general by the reference character R comprises two physically and mag-

netically separate cores 1, 2 each composed of the usual laminations or stampings, each core being substantially C-shaped and having a transverse air gap in one of its sides, the movable element 3 of the relay constituted by a circular disc being adapted to move within both such air gaps. The cores 1, 2 are so mounted within the relay casing 4 that the plane of the laminations of the core 1 is inclined at an angle of approximately 45° to the plane of the laminations of the core 2, the back leg 5 of the side of the rectangular core 1 which is opposite to the side containing the air gap being closely adjacent to the corresponding back leg 6 of the other core 2. The cores 1, 2 are supported in this position by means of an angular bracket 7 and the adjacent sides of both cores are surrounded by a common winding 8. As best shown in Fig. 2, the winding 8 is made in two sections connected in series and each surrounding the back legs 5 and 6 of both the cores 1 and 2. The opposing pole faces 10 and 11 of the core 1, and the pole faces 12 and 13 of core 2 formed at the air gaps above referred to are slotted to accommodate a local winding 9 constituted by a copper strap bent into a suitable form to surround the portions into which the pole face is divided by the slots formed therein. Referring now to Figs. 2, 3, and 4, it will be seen that the winding 9 is in the form of a letter S on pole faces 10 and 12, whereas this winding merely passes through the pole faces 11 and 13.

It will be observed that the cores 1, 2 and the fluxes traversing these cores are magnetically separate from one another, while owing to the common track winding surrounding both cores the magnetic-motive force tending to cause the two fluxes is the same for both cores, this tending to prevent any inequality between the magnitudes of the two fluxes at the predetermined frequency in a simple and effective manner.

The movable element 3 of the relay is arranged to operate relay contacts in the usual manner, the mechanism connecting the movable element 3 and these contacts being of any desired character.

The operation of the relay is as follows:—
The parts of the relay are so designed and

adjusted that when the windings 8 and 9 are supplied with alternating current of a given frequency the shifting magnetic fields are thereby caused to traverse the air gaps but 5 the opposing pole faces of the cores 1, 2 exert equal and opposite torques on the disc so that the relay contacts remain open. When the current supplied to the relay windings is of a different frequency, however, such for 10 example as a higher frequency, the torque exerted on the disc by the shifting magnetic field in the air gaps of one of the cores 1, 2 is arranged to be greater than the torque exerted on this disc by the shifting magnetic 15 field in the other air gaps, this being preferably effected by the provision of short circuited conductors 12^a and 13^a surrounding the opposing pole faces of core 2. (See Figs. 2, 3 and 4.) When the current of 20 the higher frequency referred to above is supplied to the relay windings, the short circuited conductors 12^a and 13^a reduce the amount of flux in pole faces 12 and 13, and increase the amount of flux in pole faces 25 10 and 11, so that the torque exerted on the movable element 3 by the shifting magnetic field produced by core 1 is greater than the torque exerted on this element by the shifting magnetic field produced by core 2. The 30 disc is thus caused to rotate so that the relay contacts are closed.

Relays embodying my invention are suitable for, though in no way limited to, use in railway signaling systems, such, for example, 35 as the system illustrated diagrammatically in Fig. 2. Referring to this view, the reference characters 15 and 15^a designate the track rails of a railway, which rails are divided, by means of insulated points 16, to 40 form an insulated track section A—B. These rails are supplied with alternating propulsion current from a generator G^p, the terminals of which are connected with the rails through balanced bonds 27. The rails 45 are provided, as usual, with bonds 26 to conduct the propulsion current around the insulated joints 16. Track section A—B is provided with a track circuit which is constantly supplied with alternating signaling 50 current from a generator G^s, through the medium of line wires 19 and 19^a, which wires are connected across the rails of the section by wires 20 and 20^a. Winding 8 of relay R is also connected across the rails of the 55 section A—B by wires 17 and 18, and winding 9 is constantly supplied with alternating current from generator G^s through a transformer T, the secondary of which is connected with the winding 9 and the primary 60 of which is connected with wires 19 and 19^a through the medium of wires 21 and 21^a. As shown in Fig. 1, the transformer T is located within the relay casing, but this particular arrangement is not essential. The 65 contacts of relay R may be utilized to con-

trol signaling apparatus not shown in the drawing in any suitable manner.

The propulsion current supplied by generator G^p and the signaling current supplied by generator G^s differ in frequency; for example, the propulsion current frequency may be 25 cycles per second, and the signaling current frequency may be 60 cycles per second. The relay R is so designed and proportioned that when 70 75 80 85 90 95 100 105 110 115 120 125 130 135 140 145 150 155 160 165 170 175 180 185 190 195 200 205 210 215 220 225 230 235 240 245 250 255 9999

The propulsion current supplied by generator G^p and the signaling current supplied by generator G^s differ in frequency; for example, the propulsion current frequency may be 25 cycles per second, and the signaling current frequency may be 60 cycles per second. The relay R is so designed and proportioned that when 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735

rounding both said back legs, a second winding associated with the pole faces of both said cores, short circuited conductors associated with the pole faces of one core but not with the other whereby the distribution of flux in said two air gaps due to current in each said winding varies with variations in the frequency of the current supplied to the winding, and a movable element mounted to 10 be oppositely affected by the fluxes traversing said air gaps.

3. A relay comprising two magnetizable C-shaped cores each terminating in opposed pole faces to form an air gap and located 15 in intersecting planes but having their back legs in juxtaposition, a first winding surrounding both said back legs, an element of electro-conducting material interposed in both said air gaps and movable in a plane 20 at right angles with the planes of both said cores, a second winding associated with said pole faces and arranged in such manner that when both said windings are supplied with alternating current shifting magnetic fields

are created in said two air gaps which tend 25 to move said element in opposite directions, and a contact controlled by said element.

4. A relay comprising two magnetizable C-shaped cores each terminating in opposed pole faces to form an air gap and having 30 their back legs in juxtaposition, two windings one surrounding both such back legs and the other associated with said pole faces in such manner that when the windings are supplied with alternating currents differing 35 in phase a shifting magnetic field is created in each said air gap, short circuited conductors associated with the pole faces of one said core but not the other whereby the distribution of flux in said two air gaps due to 40 current in each winding varies with variations in the frequency of the current supplied to the winding, and a movable element mounted to be oppositely affected by the shifting magnetic field in said two air gaps. 45

In testimony whereof I affix my signature.

LESLIE H. PETER.
